(57) **CLAIM**

The ornamental design for a bag, as shown and described.

DESCRIPTION

FIG. 1 is a perspective front view of a bag showing my new design;

FIG. 2 is a perspective back view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the bag in use.

Short broken lines illustrate stitching on the bag's handle and along zippers. Long broken lines of a rectangle in FIG. 9 show the bag in use and form no part of the claimed design.

Wavy lines indicate material of a flexible nature and form no part of the claimed design.
